UNITED STATES PATENT OFFICE.

EMIL KLAHN, OF NEW VERNON, NEW JERSEY.

GYRO APPARATUS.

1,309,637.

Specification of Letters Patent. Patented July 15, 1919.

Application filed November 8, 1915. Serial No. 60,191.

To all whom it may concern:

Be it known that I, EMIL KLAHN, a citizen of the United States, and resident of New Vernon, in the county of Morris and 5 State of New Jersey, have invented certain new and useful Improvements in Gyro Apparatus, of which the following is a specification.

The invention relates to gyroscopic apparatus, particularly to such wherein the axis of the rotating mass is designed to remain substantially tangential to the meridian *i. e.*, the axis will maintain a substantially north-south direction irrespective of the particular 10 latitude at which the apparatus may be located or to which it may be transported.

Instruments of this character are particularly applicable to non-magnetic or so-called "gyro-compasses" for use in navigation; and 20 the present application is more especially concerned with this embodiment of the invention, although it is to be understood that said invention is not restricted thereto but is of general application.

25 The invention has for its object to so construct a device of this character that not only will the spinning mass be automatically and rapidly returned to a north-south position when displaced therefrom, but when in this 30 position will be positively maintained therein, *i. e.* will follow the meridian under the influence of the earth's rotation and which position will, moreover, not be disturbed by a change in the latitude of the 35 place. For this purpose, the instrument is so mounted as to leave its spinning mass substantially three degrees freedom of rotation. Being free from the effects of rotary 40 impulses about its vertical axis, the gyroscope is, therefore, not subject to the influence of the vertical component of the earth's rotation.

The construction, however, is such as to 45 make the gyroscope subject, under certain conditions, to the influence of the horizontal component of the earth's rotation and to certain auxiliary influences, as will herein-after be set forth.

In the accompanying drawings, which 50 illustrate the invention—

Figure 1 is an elevation of the compass, partly in section.

Fig. 2 is a plan thereof.

Fig. 3 is a side elevation of the spinning 55 mass and mounting therefor as well as of the automatic return mechanism; and Fig. 4

is an end elevation thereof, both views being on an enlarged scale.

Fig. 5 is a vertical section through the spinning mass and a portion of its base and 60 on an enlarged scale.

Fig. 6 is a horizontal section through the spinning mass and on an enlarged scale.

Fig. 7 and Fig. 8 are vertical sections taken on the lines 7—7, and 8—8, Fig. 5, and 65 looking respectively in the directions of the arrow.

Similar characters of reference designate 70 corresponding parts throughout the several views.

In carrying out the invention, I prefer to employ a gyroscope of the type disclosed in my prior U. S. application, Serial No. 854863, filed the 3rd day of August, 1914, and driven in the manner disclosed in a 75 further application, Serial No. 854864, and filed by me the 3rd day of August, 1914. No claim, however, is made in the present application for the specific details shown in the two aforesaid applications; and it is to be 80 understood that I do not restrict myself in the present application to any particular type of gyroscope nor to the manner of driving the same.

Referring to the drawings, 10 designates 85 a supporting base or frame to which the apparatus is hung in suitable gimbal supports 11, as is well understood. The apparatus proper consists of a base portion or support 12 whose upper surface is provided with a 90 spherically dished portion 13 which is adapted to partly sustain, when the gyroscope is not in operation, a hollow cylinder 14 having its under surface similarly curved to conform to the dished portion 13 in which 95 its lower end is placed.

Under certain conditions, hereinafter more fully set forth, the said cylinder 14 may 100 rotate freely about its longitudinal (vertical) axis and, furthermore, relative motion between the support 12 and the cylinder 14 will be possible. The said cylinder, moreover, is adapted to be supported, preferably above its center of gravity upon a hollow stem 15 centrally disposed in the interior of 105 the cylinder and fixedly secured to the base portion or support 12. At its upper end, stem 15 is provided with a cone pivot 16 fitting within a guiding recess 17 of the inner surface of the cylinder top. When free 110 from said supports, cylinder 14 may rotate about its longitudinal axis, which axis passes

substantially through the pivot 16; the said axis, furthermore, constituting the vertical axis of the gyroscope. To effect this freedom from its support, the cylinder 14 is 5 adapted to be sustained by a suitable fluid as, for example, air under proper pressure, said fluid being conducted into the interior of the cylinder from a suitable supply (not shown) through a connection 18 and the 10 said hollow stem 15 and lateral openings 19 at the outer end of said stem. About the end of the stem is attached a hollow cap 20 which carries also the pivot 16, and this cap is provided with lateral openings 21 15 and upper openings 22 discharging into the interior of the cylinder. The cap 20 is vertically slidable upon the stem 15, its lowermost position being fixed by means of an abutment or stop 23 of the stem. To limit 20 the upward movement of said cap, the same is provided with a lug or ring 24 which is adapted to engage with upwardly extending fingers 25 of a nut 26 screwed upon the abutment 23, a spring 27 being interposed 25 between the cap 20 and the abutment 23 to assist the fluid pressure in freeing the cylinder 14 from support 12. By means of the foregoing, the vertical movement of the cap 20 under the action of the incoming 30 fluid may be restricted to that necessary to properly guide, or rather prevent, the cylinder 14 from any possibility of displacement of its proper vertical position through the coöperation of the cone 16 and recess 35 17. It is understood, however, that there will be no actual contact, but that the cylinder 14 is sustained by the column of air within and all friction thereby eliminated. When the air support is withdrawn, the 40 adjustment is such that the entire cylinder and other mechanism hereinafter described will be sustained substantially by the support or base 12 rather than by the cap 20 and stem 15. On restoring the air support, the 45 spring 27 will serve, also, to cause the cap to follow the upward movement of said cylinder until it abuts the fingers.

The cylinder 14 carries at its top, as by 50 means of suitable standards 30 and other mechanism hereinafter set forth, a hollow rotatable spinning mass 31 which is in the form of a sphere or a portion thereof and constructed in separable halves, and with its center coinciding substantially with the 55 center of rotation. The periphery of said mass is perfectly smooth and is adapted to run in a corresponding spherical cavity 32 of the upper portion of said cylinder. The extent of said cavity surface may be varied to suit the different applications of 60 the apparatus, and the said mass is so mounted with respect to the said cavity, as to leave a shallow passage-way 33 between its periphery and the surface of said cavity. 65 The two said surfaces are mounted concen-

trically, the radius of curvature of one being slightly greater than the other—the exact difference for best results being determined by trial and computation.

The fluid to effect the rotation of mass 70 31 is arranged to be directed into the passage-way 33 through a suitable nozzle 34, preferably flat and which communicates with the interior 14 through a duct 35, the said nozzle, when the mass 31 is in the plane 75 of the meridian, being directed substantially at a tangent to the surface of cavity 32 and symmetrically disposed with respect to the plane of the equator of said rotating mass. A stream of fluid is delivered thereby into 80 the passage-way 33 in the nature of a band and of which there will not be an appreciable lateral flaring as it passes therethrough, imparting its velocity to the mass 31 and, also, counteracting the weight of said mass 85 relatively to the cylinder. The spinning mass, therefore, floats substantially free in space above the cylinder 14, the latter being similarly supported as aforesaid with respect to the base or support 12. 90

To the cylinder 14 is fixedly attached a suitable arm or pointer 36 adapted to coöperate with a compass card or ring 37 graduated in the usual manner. The card 37 is fixedly attached to the gimbal support 11 95 whereby relative rotation between the card and pointer (gyroscope) may be conveniently measured. A horizontal rod or shaft 40 is supported by the standards 30 and about the same is mounted for rotation the 100 spinning mass 31 which runs upon a frame or cradle 41 mounted to oscillate about said shaft and within the interior of said mass. Suitable ball bearings 42 are provided for this purpose and are fitted upon sleeves 43 105 which extend outwardly from opposite sides of the frame 41 and through which passes the said shaft 40, the inner diameter of said sleeves being sufficient to permit of the required oscillation of the frame 41 and spinning mass 31 carried thereon. 110

The frame 41 is arranged to oscillate about an axis perpendicular to the axis of shaft 40, that is, the cradle will rock in a plane at right angles to the plane of rotation of the spinning mass, as by means of suitable pivots 44 extending inwardly from opposite ends of said frame into the said shaft. The spinning mass may thus rotate freely about a horizontal axis represented 120 by the shaft 40, upon the ball bearings 42, and may rock as a whole with the frame 41 about the pivots 44 perpendicular thereto. The cylinder portion 14, upon which said spinning mass is mounted, is perfectly free 125 to rotate about a vertical axis when the air is applied, and the gyroscope, therefore, possesses the desired three degrees of freedom of rotation. By the mounting hereinbefore described, the spinning mass will be in neu- 130

tral equilibrium, its center of gravity coinciding with its center of rotation, and a perfect balance thereof is insured, the said mass with its supporting cylinder 14 rotating substantially freely in space. The apparatus is, therefore, not susceptible to pendulous effects originating in the gimbal mountings or to other motions of the support 12; and any pendulous motions of the cylinder 14 itself would, furthermore, be without effect upon the spinning mass 31, in view of the hereinbefore described novel suspension. Barring purely accidental disturbances, therefore, the said cylinder is continually maintained in the plumb line.

Being thus freely suspended, the gyroscope is entirely free from the effects of rotary influences about its vertical axis and is, therefore, not affected by the vertical component of the earth's rotation. With respect to the horizontal component of the earth's rotation, provision is made whereby the same may be employed to automatically affect the gyroscope to cause its axis to follow the meridian, that is to say, the said component will be effective in producing a precessional force as soon as the axis of rotation of the gyroscope is thrown out or tends to leave the plane of the meridian. This effect is obtained without destroying the freedom of rotation of the gyroscope about the three axes.

To this end, there is mounted upon the shaft 40 and in the plane of the axis of said shaft a segmental gear 50 whose teeth engage the teeth of a pinion 51 mounted upon a freely rotatable shaft 52 carried by the cradle frame 41. To this shaft and upon both sides of the said pinion are fixedly attached segmental gears 53 whose teeth engage with the teeth of pinions 54 mounted to be freely rotatable upon the pivots 44 for the cradle or frame 41, or about an axis perpendicular to the shaft 40. So far as the actual resistance to the rocking of said cradle or frame affects the freedom of the gyroscope, the gearing hereinbefore described is substantially without effect, and the gyroscope will continue to possess the desired three degrees of freedom of rotation. Nevertheless, the lateral thrust developed in the transmission of the earth's rotation through this gearing will be sufficient to affect said frame 41, producing thereby a precession of the gyroscope, as hereinafter set forth. When the axis of rotation of mass 31 is displaced from, or swings out of, its position in the meridian—being directionally unchanged in absolute space—the mass 31 will assume an apparent (i. e. relatively to the earth) tilt about a horizontal axis to a degree depending upon the extent or the angle of the displacement, while the shaft 40 remains horizontal. This apparent tilting of the mass 31 relatively to

the shaft 40, which latter follows the earth's rotation, being also relative to the gear wheel 50 which is attached to said shaft, is transmitted through the pinion 51, gears 53 and pinions 54. In this transmission, a lateral thrust through the teeth is exerted upon the respective carrying shafts and bearings, and depending upon the ratio of the transmission and the form of the teeth. This lateral thrust reacts upon the frame or cradle 41 to effect an actual (i. e. relatively to absolute space) tilt of the same about the pivots 44. If this ratio be made large enough, the side trains may be omitted, and I do not wish to restrict myself to any particular type or combination of gears to effect the desired lateral precessional force. This tilting of the cradle 41 will be communicated to the mass 31 attached thereto and effect a precession thereof, which precession in due course returns the said mass to the meridian position.

When the mass 31 is considerably displaced from the meridian, the precession produced, as hereinbefore explained, though appreciable, may be insufficient to effect a speedy restoration of the said mass to its meridian position. Additional means to accelerate the return are, therefore, provided, reference being had more particularly to Figs. 3 and 4 of the drawings. As shown therein, the standards 30 are each provided with a bracket 61 extending outwardly and carrying suitable means for producing precession, for example, weights 62, slidably mounted therein for vertical movement. A frame 63, connected to the cradle or frame 41 and movable therewith, extends about each end of said shaft 40 and about the standards 30. To said frames 63 are attached upwardly directed contact members or plates 64 whose surfaces are normally out of contact with the bottom of the weights 62, but are adapted to coöperate therewith when the frame 41 is correspondingly tilted. One or the other of the weights 62 will then be engaged by its corresponding plate 64, which will bear the same and will communicate through frames 63 and 41, the pressure exerted thereby, to the mass 31, overbalancing the same, and rapidly effect its precession to the meridian position.

I claim:—

1. The combination with a gyroscope, mounted in substantially three degrees of freedom of rotation; of gearing, in connection therewith, having a predetermined velocity ratio and so mounted as to develop a lateral thrust, when affected by the horizontal component of the earth's rotation, to produce precession of the gyroscope.
2. The combination with a gyroscope, mounted in substantially three degrees of freedom of rotation; of a shaft with respect to which the rotatable mass of said gyro-

scope may be tilted; and gearing connecting said shaft with the rotatable mass of the gyroscope, said gearing being rotatable in a plane perpendicular to the plane of rotation of said mass.

3. The combination with a gyroscope, mounted in substantially three degrees of freedom of rotation; of a shaft with respect to which the rotatable mass of said gyroscope may be tilted; a pair of gear wheels on said shaft and rotatable therewith in the plane of said shaft, and two pairs of gear wheels, one upon each side of said first-named pair, connecting the same with said 15 rotatable mass.

4. The combination with a gyroscope, mounted in substantially three degrees of freedom of rotation; of a shaft with respect to which the rotatable mass of said gyroscope may be tilted, a segmental gear fixed to said shaft in the plane of its axis, a pinion meshing therewith, a shaft driven by said pinion, two segmental gears, one upon each side of said pinion and rotatable with 20 said pinion shaft, and two pinions carried by said rotatable mass and freely rotatable relatively thereto, said two pinions meshing with the respective said two segmental gears.

5. The combination with a gyroscope, comprising a mass free to rotate about two mutually perpendicular axes, and a support therefor freely rotatable about a vertical axis; of a shaft carried by said support and upon which said rotatable mass may be 30 tilted about an axis perpendicular to said shaft; and gearing driven by said shaft and connecting the same to said rotatable mass, said gearing being rotatable in a plane perpendicular to the plane of rotation of said 35 mass.

6. The combination with a gyroscope, comprising a mass free to rotate about two mutually perpendicular axes, and a support therefor freely rotatable about a vertical axis; of a shaft carried by said support; a cradle pivotally attached to said shaft to rock about an axis perpendicular thereto and upon which cradle is rotatably mounted said mass; and gearing driven by said shaft, rotatable in a plane perpendicular to the plane 45 of rotation of said mass and connecting said shaft with said cradle.

7. The combination with a gyroscope, comprising a mass free to rotate about two mutually perpendicular axes, and a support therefor freely rotatable about a vertical axis; of a shaft carried by said support; a cradle pivotally attached to said shaft to rock about an axis perpendicular thereto and 55 upon which cradle is rotatably mounted said mass; gear wheels carried by said shaft and driven thereby; and gear wheels carried by said cradle and meshing with said first-named gear wheels.

8. The combination with a gyroscope, com-

prising a mass free to rotate about two mutually perpendicular axes, and a support therefor freely rotatable about a vertical axis; a cradle pivotally attached to said shaft to rock about an axis perpendicular thereto and upon which cradle is rotatably mounted said mass; a segmental gear fixed to said shaft in the plane of its axis, a pinion meshing therewith, a shaft driven by said pinion, two segmental gears, one upon each side of said pinion and rotatable with 70 said pinion shaft, and two pinions carried by said cradle and freely rotatable relatively thereto, said two pinions meshing with the respective said two segmental gears. 80

9. The combination with a gyroscope including a hollow, rotatable shell mounted in substantially three degrees of freedom of rotation; of means contained therein, subject to the effect of the horizontal component 85 of the earth's rotation, to impart to the said gyroscope a precession producing force through the action of said horizontal component on said means.

10. The combination with a gyroscope comprising a hollow, rotatable shell free to rotate about two mutually perpendicular horizontal axes, and a support therefor freely rotatable about a vertical axis; of a shaft carried by said support and passing 90 through said shell; a cradle mounted within said shell, pivotally attached to said shaft to rock about an axis perpendicular thereto and upon which cradle said mass is rotatably mounted; and gearing driven by said shaft, 100 rotatable in a plane perpendicular to the plane of rotation of said shell and connecting the shaft with said cradle.

11. The combination with a gyroscope comprising a hollow, rotatable shell free to 105 rotate about two mutually perpendicular horizontal axes, and a support therefor freely rotatable about a vertical axis; of a shaft carried by said support and passing through said shell; a cradle mounted within 110 said shell, pivotally attached to said shaft to rock about an axis perpendicular thereto and upon which cradle said mass is rotatably mounted; a segmental gear fixed to said shaft in the plane of its axis, a pinion meshing therewith, a shaft driven by said pinion, two segmental gears, one upon each 115 side of said pinion and rotatable with said pinion shaft, and two pinions carried by said cradle and freely rotatable relatively thereto, said two pinions meshing with the respective said two segmental gears.

12. The combination with a gyroscope comprising an air supported mass free to 120 rotate about two mutually perpendicular horizontal axes, and an air supporting carrying member therefor free to rotate about a vertical axis; of means, subject to the effect of the horizontal component of the earth's rotation, to impart to the said gyro- 125 130

scope a precession producing force through the action of said horizontal component on said means.

13. The combination with a gyroscope comprising an air supported mass free to rotate about two mutually perpendicular horizontal axes, and an air supported carrying member therefor free to rotate about a vertical axis; of gearing, subject to the effect of the horizontal component of the earth's rotation, to impart to the gyroscope a precession producing force through the action of said component on said gearing.

14. The combination with a gyroscope comprising an air supported mass free to rotate about two mutually perpendicular horizontal axes, and an air supported carrying member therefor free to rotate about a vertical axis; of a shaft supported by 20 said carrying member; a cradle pivotally attached to said shaft to rock about an axis perpendicular thereto and upon which cradle is rotatably mounted said mass; and gearing driven by said shaft and rotatable 25 in a plane perpendicular to the plane of rotation of said mass and connecting the shaft with said cradle.

15. The combination with a gyroscope, comprising a mass free to rotate about two 30 mutually perpendicular horizontal axes, means to direct a stream of air thereto to effect the spinning of the same, and an air supported carrying member for said mass and freely rotatable about a vertical axis; of means, subject to the effect of the horizontal component of the earth's rotation, to impart to the said gyroscope a precession producing force through the action of said horizontal component on said means.

16. The combination with a gyroscope comprising a mass free to rotate about two mutually perpendicular horizontal axes; a carrying member for said mass and freely rotatable about a vertical axis; and means 40 to direct a stream of air to said carrying member and to said rotatable mass to sustain the former and effect the spinning of the latter; of means, subject to the effect of the horizontal component of the earth's 45 rotation, to impart to the said gyroscope a precession producing force through the action of the said horizontal component on said means.

17. The combination with a gyroscope comprising a hollow, rotatable shell, a hollow rotatable air sustained support therefor, and a nozzle to direct air for driving said shell, said nozzle being carried by said support and communicating with the interior thereof; of means, subject to the effect of the horizontal component of the earth's rotation, to impart to the said gyroscope a precession producing force through the action of said horizontal component on said 65 means.

18. The combination with a gyroscope comprising a rotatable mass consisting of a portion of a sphere, a rotatable support therefor having a spherical cavity, concentric with said mass but of greater radius 70 of curvature, to provide a passage-way, and a nozzle carried by said support to direct a stream of air into said passage-way to effect the spinning of said mass; of means, subject to the effect of the horizontal component of the earth's rotation, to impart to the said gyroscope a precession producing force through the action of said horizontal component on said means.

19. The combination with a gyroscope 80 comprising a rotatable mass consisting of a portion of a sphere, a rotatable, hollow support therefor having a spherical cavity, concentric with said mass but of greater radius 85 of curvature to provide a passage-way, a nozzle carried by said support and communicating with its interior to direct a stream of air into said passage-way to effect the spinning of said mass, and means to admit air to the interior of said support; of gearing 90 connecting said support with said rotatable mass, said gearing being rotatable in a plane perpendicular to the plane of rotation of said mass.

20. The combination with a gyroscope 95 comprising a rotatable mass consisting of a portion of a sphere, a rotatable, hollow fluid sustained support therefor terminating in a spherical surface at the bottom and having a suitable recess in its internal upper 100 surface, a frame provided with a spherical cavity to receive the lower end of said support, a stem carried by said frame, extending into said support and terminating in a suitable pivot adapted to coöperate with the 105 said recess in the internal surface of the support; of gearing connecting said support with said rotatable mass, said gearing being rotatable in a plane perpendicular to the plane of rotation of said mass.

21. The combination with a gyroscope comprising a rotatable mass consisting of a portion of a sphere, a rotatable, hollow, fluid sustained support therefor terminating in a spherical surface at the bottom and having 115 a suitable recess in its internal upper surface, a frame provided with a spherical cavity to receive the lower end of said support, a stem carried by said frame and extending into said support, a vertically movable cap 120 thereon, provided with suitable openings and with a pivot to coöperate with said recess, resilient means tending to force said cap upwardly, and means to limit the upward movement of said cap; of gearing 125 connecting said support with said rotatable mass, said gearing being rotatable in a plane perpendicular to the plane of rotation of said mass.

22. The combination with a gyroscope 130

comprising a rotatable mass consisting of a portion of a sphere, a rotatable, hollow support therefor having a spherical cavity, concentric with said mass but of greater radius of curvature to provide a passage-way, a nozzle carried by said support and communicating with its interior to direct a stream of air into said passage-way to effect the spinning of said mass, and means to admit air to the interior of said support; of a shaft carried by said hollow rotatable support; a cradle pivotally attached to said shaft to rock about an axis perpendicular thereto and upon which cradle is rotatably mounted said mass; and gearing driven through said shaft and rotatable in a plane perpendicular to the plane of rotation of said mass and connecting said shaft with said cradle.

23. The combination with a gyroscope comprising a rotatable mass consisting of a portion of a sphere, a rotatable, hollow support therefor having a spherical cavity, concentric with said mass but of greater radius of curvature to provide a passage-way, a nozzle carried by said support and communicating with its interior to direct a stream of air into said passage-way to effect the spinning of said mass, and means to admit air to the interior of said support; of a shaft carried by said hollow rotatable support; a cradle pivotally attached to said shaft to rock about an axis perpendicular thereto and upon which cradle is rotatably mounted said mass; a segmental gear fixed to said shaft in the plane of its axis, a pinion meshing therewith, a shaft driven by said pinion, two segmental gears, one upon each side of said pinion and rotatable with said pinion shaft, and two pinions carried by said cradle and freely rotatable relatively thereto, said two pinions meshing with the respective said two segmental gears.

24. The combination with a gyroscope comprising a rotatable mass consisting of a portion of a sphere, a rotatable, hollow, fluid sustained support therefor, terminating in a spherical surface at the bottom and having a suitable recess in its internal upper surface to provide a passage-way, a frame provided with a spherical cavity to receive the lower end of said support, a stem carried by said frame and extending into said support, a vertically movable cap thereon, provided with suitable openings and with a pivot to coöperate with said recess, resilient means tending to force said cap upwardly, and means to limit the upward movement of said cap; a nozzle carried by said support and communicating with its interior to direct a stream of fluid into said passage-way to effect the spinning of said mass, means to admit fluid to said stem; of a shaft carried by said hollow rotatable support; a cradle pivotally attached to said shaft to rock about an axis perpendicular thereto and upon

which cradle is rotatably mounted said mass, a segmental gear fixed to said shaft in the plane of its axis, a pinion meshing therewith, a shaft driven by said pinion, two segmental gears, one upon each side of said pinion and rotatable with said pinion shaft, and two pinions carried by said cradle and freely rotatable relatively thereto, said two pinions meshing with the respective said two segmental gears.

25. The combination with a gyroscope mounted in substantially three degrees of freedom of rotation; of means, subject to the effect of the horizontal component of the earth's rotation, to impart to the gyroscope a precession producing force through the action of said component on said means; and supplementary precession producing means.

26. The combination with a gyroscope comprising a mass free to rotate about two mutually perpendicular horizontal axes, and a support therefor freely rotatable about a vertical axis; of means, subject to the effect of the horizontal component of the earth's rotation, to impart to the gyroscope a precession producing force through the action of said component on said means; and supplementary means to engage with said gyroscope to effect precession of the same.

27. The combination with a gyroscope comprising a mass free to rotate about two mutually perpendicular horizontal axes and having its center of gravity coinciding with its center of rotation, and a support therefor freely rotatable about a vertical axis and having its center of gravity in its axis of rotation; of means, subject to the effect of the horizontal component of the earth's rotation, to impart to the gyroscope a precession producing force through the action of said component on said means; and supplementary means to engage with said gyroscope to effect precession of the same.

28. The combination with a gyroscope mounted in substantially three degrees of freedom of rotation; of means, subject to the effect of the horizontal component of the earth's rotation, to impart to the gyroscope a precession producing force through the action of said component on said means; and auxiliary mass to engage with said gyroscope to effect precession of the same.

29. The combination with a gyroscope mounted in substantially three degrees of freedom of rotation; of means, subject to the effect of the horizontal component of the earth's rotation, to impart to the gyroscope a precession producing force through the action of the said component on said means; and vertically slidable masses mounted upon opposite sides of the gyroscope adapted to engage therewith to effect precession of the same.

30. The combination with a gyroscope

- comprising a mass free to rotate about two mutually perpendicular horizontal axes, and a support therefor freely rotatable about a vertical axis; of gearing in connection therewith and so mounted as to develop a lateral thrust, when affected by the horizontal component of the earth's rotation, to impart to the gyroscope a precession producing force; vertically slidable masses mounted upon opposite sides of the gyroscope; and means carried by the gyroscope to engage and support said masses.
31. The combination with a gyroscope comprising a mass free to rotate about two mutually perpendicular axes, and a support therefor freely rotatable about a vertical axis; of a shaft carried by said support; a cradle pivotally attached to said shaft to rock about an axis perpendicular thereto and upon which cradle is rotatably mounted said mass; of gearing driven by said shaft, rotatable in a plane perpendicular to the plane of rotation of said mass and connecting said shaft with said cradle; suitable brackets carried by the support for the rotating mass, and weights slidable therein; and suitable supports carried by the cradle adapted to engage and support said weights.
32. The combination with a gyroscope mounted in substantially three degrees of freedom of rotation; of means normally without effect upon the gyroscope, adapted to be engaged by the said gyroscope to affect its equilibrium and thereby produce a precession thereof when the gyroscope has been disturbed a predetermined amount.
33. The combination with a gyroscope mounted in substantially three degrees of freedom of rotation; of auxiliary mass, normally without effect upon the gyroscope, to engage with the said gyroscope to produce precession of the same.
34. The combination with a gyroscope mounted in substantially three degrees of freedom of rotation; of vertically slidable masses mounted upon opposite sides of the gyroscope adapted to engage therewith to produce precession of the same.
35. The combination with a gyroscope comprising a mass free to rotate about two mutually perpendicular axes, and a support therefor freely rotatable about a vertical axis; of a shaft carried by said support; a cradle pivotally attached to said shaft to rock about an axis perpendicular thereto and upon which cradle is rotatably mounted said mass; suitable brackets carried by the support for the rotating mass, and weights slidable therein; and suitable supports carried by the cradle adapted to engage and support said weights.

Signed at New York, in the county of New York, and State of New York, this 5th day of November, A. D. 1915.

EMIL KLAHN.
